United States Patent Office.

JUSTIN E. SMITH AND MARK H. DASENBROOK, OF WARRENVILLE, ILLINOIS.

Letters Patent No. 78,900, dated June 16, 1868.

IMPROVED WEATHER-STRIP.

The Schedule referred to in these Letters Patent and making part of the same.

TO ALL WHOM IT MAY CONCERN:

Be it known that we, JUSTIN E. SMITH and MARK H. DASENBROOK, of Warrenville, in the county of Du Page, and State of Illinois, have invented a new and useful Improvement in Weather-Strips; and we do hereby declare and make known that the following is a full, clear, and exact description of the same, reference being had to the accompanying drawings, and the letters and figures marked thereon, which form part of this specification.

Our said invention consists in a novel arrangement for closing the space between the threshold and the door, for the purpose of excluding the cold, rains, dust, or snow from the house, which weather-strip automatically closes said space when the door is closed together, but does not in any manner interfere with the opening of the door when desired, this invention being an improvement upon the device patented by E. C. Mathewson, May 16, 1848.

To enable those skilled in the art to understand how to construct and use our said invention, we will proceed to describe the same with particularity, making reference in so doing to the aforesaid drawings, in which—

Figure 1 represents a front view of our invention, the door being opened, showing also a roller upon the jamb to close the strip, and

Figure 2 is a vertical section of the same.

Similar letters of reference denote the same parts of our invention in the different figures.

P represents the door, hinged at R R to the jamb or casing, and closing against the stops C, and over the threshold E, as shown in the drawings.

Near the lower edge of the door is secured, by screws passing through holes in its upper edge, a metallic strip, B, its lower edge, when forced down, as hereinafter described, resting closely upon the door-sill E, but rising above the bottom of the door, when the door is open, as hereinafter specified.

The strip B is secured to the door by the screws c, or otherwise, so as to move thereupon as upon a hinge, as hereinafter set forth.

Above the strip B is secured another strip, D, its edge projecting over the strip B, as shown, to keep the rain from entering the joint of the strip B and entering the house.

In a recess made in the door, beneath the said strips, as indicated in the drawings, is arranged a spiral spring, S, one end of which rests against the upper end of said recess, while to the other end of said spring is secured a bar, s, which is itself secured to an arm, b, attached to the strip B, as clearly shown in fig. 2.

By this arrangement it will be seen that the spring S acts to throw the lower edge of the strip B up from the door-sill, and retain it up while the door remains open.

Upon that side of the door opposite the hinges there is arranged a small roller, W, fastened to the jamb by a screw, or other pin, so that said roller may freely turn or revolve.

The object of this roller is to press down the strip B when the door is closed, to press its lower edge upon the door-sill.

When the door is being closed, the lower edge of the strip B passes beneath the roller, and is thereby gradually forced down as the door continues to close, until, when the door is shut, the edge of the strip B lies closely down upon the door-sill, thus effectually closing the space beneath the door, excluding the cold, snow, wind, dust, or rain, as desired.

We claim the combination of the strips D B, spring S, arranged in a recess, as shown, when said spring is operated by the rod s and arm b, in the manner and for the purposes specified.

JUSTIN E. SMITH,
MARK H. DASENBROOK.
